[57] **CLAIM**

The ornamental design for a wall-mounted soap dish, as shown and described.

DESCRIPTION

FIG. 1 is a top perspective view of a wall-mounted soap dish showing my new design;

FIG. 2 is a top plan view thereof;

FIG. 3 is a front elevational view thereof;

FIG. 4 is a right side elevational view thereof, the left side elevational view being the mirror image of FIG. 4;

FIG. 5 is a bottom plan view thereof; and

FIG. 6 is a rear elevational view thereof.

FIG. 1

FIG. 2

FIG. 3

FIG. 4

FIG. 5

FIG. 6
